US00D947179S

(12) **United States Design Patent** (10) **Patent No.:** **US D947,179 S**
(45) **Date of Patent:** **** Mar. 29, 2022**

(54) **SMART WATCH BODY**

(71) Applicant: **RYEEX Technology Co., Ltd.**,
Shenzhen (CN)

(72) Inventor: **Mingjun Yin**, Shenzhen (CN)

(73) Assignee: **RYEEX TECHNOLOGY CO., LTD.**,
Shenzhen (CN)

(**) Term: **15 Years**

(21) Appl. No.: **29/748,796**

(22) Filed: **Sep. 1, 2020**

(30) **Foreign Application Priority Data**

Jul. 9, 2020 (CN) 202030369948.0

(51) **LOC (13) Cl.** **14-02**
